TUBE CLEANER

James P. Rodgers, Bloomfield, N. J., assignor to
The Roto Company, Newark, N. J., a corpora-
tion of New Jersey

Application December 13, 1935, Serial No. 54,202

13 Claims. (Cl. 15—104.12)

The invention relates to tube cleaners for cleaning debris and undesired deposits which form in tubular equipment, such as condensers, evaporators, boilers, pasteurizers, and other devices. 5 The invention to be described herein is particularly suited for cleaning the tubes of pasteurizers for milk in which a deposit from the milk is left which is relatively soft and gummy.

Pasteurizer tubes may be of stainless steel having a high polish on the inside surface, or may be tubes of any suitable material which are nickel plated, or may be copper tubes which are tin lined. These tubes, of course, must be thoroughly and frequently cleaned in order to preserve the 10 purity of the next batch of milk which passes through the pasteurizer, but in cleaning these tubes, the inner surfaces must not be scratched or marred in any way. The tubes or pipes are also flushed with water in order to thoroughly 20 clean them.

The invention also relates to the combination of a tube cleaner with a valve mechanism for controlling the power fluid for the motor and also for controlling the flow of water where provision is made with the cleaner for the flow of water during the operation of the cleaner.

It is an object of the invention to construct a tube cleaner in which a stream of water or other liquid is provided in front of the air motor, which 30 stream of water or liquid is provided in a new and novel manner.

Another object of the invention is to provide a tube cleaner particularly adapted for pasteurizers in which it is important that in no event 35 should the inner surface of the tube be marred or scarred in any way, and in which a flexible coupling is used with a cleaning tool in conjunction with the cleaner which will not release a metallic part in case of wear or breakage of the 40 flexible coupling.

Another object of the invention is to provide a tube cleaner in conjunction with a valve mechanism in which it is impossible for the valve to be moved to another position so long as the valve 45 is in the tube. In the particular construction herein, a valve mechanism is retained in open position so that the source of power cannot be turned off and if water or other liquid is also provided, so that the water or liquid may not be turned off so long as the valve and cleaner are 50 within the tube.

Another object is to provide a spray of water or other liquid at the front end of a power driven tube cleaner, which spray of water is given a 55

swirling effect in order to augment its flushing and cleaning action.

Other objects of the invention will be more apparent from the following description, taken in connection with the accompanying drawings 6 showing a preferred embodiment of the invention, in which:

Figure 1 is a longitudinal section through the motor, water spraying and valve mechanism with the cleaning tool detached from the motor. 10

Figure 2 is a view showing the cleaning tool particularly adapted to be attached to the end of the motor of Figure 1 with a flexible coupling provided between the tool and the motor. The flexible coupling illustrated is particularly applicable for use with pasteurizers and like tubular apparatus and is shown in longitudinal section. 15

Figure 3 is a cross section through the valve means taken on line 3—3 of Figure 1, excepting that the valve means is shown in closed position. 20 The valve means is also shown in relation with a tube for which this valve means and cleaner are adapted to be used, the tube being shown in dot and dash lines.

Figure 4 is a cross section through the motor, 25 taken on line 4—4 of Figure 1, and shows the water passage leading to the water outlets and also the water outlets.

Figure 5 is a cross section through the motor, taken on line 5—5 of Figure 1, and shows the exhaust for the motor and the water outlets. 30

Figure 6 is a plan view of the valve means disconnected from the motor with the valves in open position as shown in Figure 1.

Figure 7 is a plan view, partially in section, 35 through the water outlet ports as taken on line 7—7 of Figure 4 along an arcuate path through the water outlets in order to show their angular direction.

The invention to be described herein utilizes 40 an air motor for driving the cleaning tool. Any type of fluid motor is contemplated in connection with the combination thereof with a valve mechanism which will be described. The motor preferred in connection with the water or liquid spraying feature is a compressible fluid motor as will be discussed more fully hereinafter. 45

The particular air or steam motor illustrated is provided with a shaft 10 in which shaft there is a slot 11 to receive a piston or power blade 12 50 which is freely slideable in the slot. One end of the shaft 10 is rotatably retained in a bearing in the front of an air cylinder 13. The cylinder 13 is provided with a bore 14 which is eccentric with respect to the shaft 10, and the periphery of the 55

shaft contacts with the wall of this bore 14, but contacts so as to enable it to rotate freely. The bore 14 is preferably substantially oval in cross section so that it is suitable for a single blade 12.

5 The rear or inward end of the shaft 10 is rotatably supported by an end cap 17 which also seals the end of the cylinder bore 14. The end cap 17 abuts against a shoulder 18 carried by the cylinder 13 and is held in this position by the nut 10 or abutting sleeve 19 having external threads 20 which are received by the internal threads 21 on the cylinder. A pin 26 in the cylinder and end cap is used to align the inlet ports therein. The sleeve 19 carries a bore 22 for the passage of air 10 to the cylinder of the air motor, which air passes through a port 23 in the end cap 17 and then through a port 24 into the bore of the cylinder 13. An exhaust port 25 is provided from the front of the cylinder and motor. The sleeve 19 is designed 15 with the bore 22 large enough at the end which engages the end cap 17 so that, when the end cap is clamped between the sleeve and the cylinder, the bore will have fluid connection with the port 24 regardless of in what rotative position of the abutting sleeve such clamping action is obtained. The sleeve 19 also has a cylindrical outer periphery at one end, excepting for a pair of flats for a wrench, and a flat end the purpose of which will appear more fully hereinafter.

20 The air motor which has been described is known in its fundamental construction and operation. Changes have been made in details of the motor construction to particularly adapt it for the service to be described herein. These 25 changes do not alter the principle or operation of the motor per se, but relate to details dictated by the new features added to the motor and dictated by the valve mechanism for controlling both the power fluid and the water. It is believed, for this reason, that a detailed description of the operation of this motor need not be given. It is to be understood also that any other type of compressible fluid or air motor is contemplated.

25 The front end of the cylinder 13 is reduced in diameter in order to form a land or shoulder 30. An outer sleeve or shell 31 has a flange 32 at the front end thereof which is received on the land 30, in order to support the front end of the shell 31 and hold the same spaced from the outer circumference of the cylinder 13. At least one outlet and preferably a plurality of outlets 33 is provided in the flange at the front face or end of the motor which outlets communicate or connect with the space 34. The outlets 35 preferably are directed at an angle, as shown in Figure 7, and are also preferably directed at an angle in the direction of rotation of the air motor. The outlets are so placed that they are in the 30 front face of the motor between the outer periphery of the motor and the shaft. In the broader aspect of the invention any form of outlet or outlets 35 is contemplated, as well as any construction providing a fluid connection or passage with the outlet or outlets.

35 The passage 34 and outlets 35 are designed to carry water or liquid to the front of the motor and preferably the outlets are provided in the front face thereof. The water is given a swirling 40 action as a consequence of the angular direction of the ports or outlets 35, which swirling and scrubbing action of the water is aided by the high velocity of the air exhausting from the air motor through the exhaust port 25. The water 45 and air flush the tube being cleaned and the

cleaning tool or brush, as the same is rotated by the motor, to loosen the deposit on the tubes and to loosen and flush any gummy particles or other debris from the cleaning tool and from the tube being cleaned.

5 The rear end of the shell 31 carries screw threads 38 which screw threads are adapted to receive the threaded end of a plug 39. This plug is shown as being a part of a valve means which will be described more fully hereinafter. It is 10 to be understood that the plug may be a separate part if desired. The plug has a countersink 40 which receives the cylindrical end of the abutting sleeve 19 to hold the rear end of the shell 31 in proper spaced relation with respect to 15 the cylinder 13 of the air motor. The bottom face 41 of the countersink of the plug 39 abuts against the end of the nut 19 so that the air motor is clamped between the flange 32 on the front end of the shell 31 and the face 41 of the 20 plug.

20 The construction described above provides a substantially air-tight and water-tight seal between the abutting sleeve 19 and the plug 39 by the abutting face 41 of the plug 39 engaging the 25 end face of the abutting sleeve 19. In this connection, it will also be observed that in use the air pressure in the bore 22 of the sleeve 19 is generally higher than the water pressure and consequently this air pressure would probably 30 keep the water out of the air motor, even if the seal were not tight. The water seal between the abutting sleeve 19 and the plug 39 is further aided by the contact of the cylindrical surface of the countersink 40 and the outer circumference of the cylindrical portion of the sleeve 19. Excepting for relatively small flats on this circumference of the sleeve 19, in order to screw the sleeve into the cylinder 13, the circumference of the abutting sleeve 19 and of the countersink 40 is relatively snug, although free relative rotation between these two parts is provided.

25 The shoulder 30 on the front of the air motor and the flange 32 on the shell 31 engage each other to form a water-tight or substantially water-tight connection, although there is no reason for the engagement being positively water-tight. It is desired that the water pass out through the outlets 35 without loss of pressure and in the direction of the outlets.

30 It has been pointed out hereinbefore that the plug 39 is carried by and forms a part of a valve means which will be generally designated by the numeral 45. The valve means has an air passage 46 which preferably is drilled lengthwise of the valve means and it connects with an angular air passage 47 which brings the outlet for this air passage to the central axis of the valve means so that it opens into the bore 22 of the nut 19. 60

35 A water passage 52 is also provided preferably by drilling a hole longitudinally through the valve means, and the end of this water passage has an angular water passage 53 carrying the passage to the outer periphery of the plug 39 or the valve 65 means since, in the illustrated embodiment, the valve means and plug are shown as integral. A second longitudinal water passage 54 along the outer periphery of the plug 39 connects this passage with the passage or space 34 around the periphery of the air motor and between the latter and the inner wall of the casing or shell 31. It will be observed that this water passage 54 will connect with the water space or passage 34, irrespective of where the passage 34 stops in its 70

rotation as the plug is threadedly tightened upon the air motor.

The valve means preferably uses a single taper plug valve 57 for controlling both the water and the air. The taper of the plug holds the same in position in one direction and a washer 58 secured at the small end of the taper plug, such as by peening over a reduced part of the end of the plug, holds the same from being removed in the other direction. The plug is provided with an air passage 59 and a water passage 60. By rotation of the plug, the air and water may be cut off from the motor.

Although a single plug 57 is preferably provided to simultaneously control both the air and the water, it will be understood that separately controlled valves of any type may be provided, as desired. The air passage 46 is adapted to be connected to a source of air pressure through any suitable connection, that shown utilizing a nipple 61 secured to an air hose 62. Similarly, the water passage 52 is connected with any suitable source of water supply, preferably by means of a nipple 63 which is secured to a water hose 64. The nipples 61 and 63 are screw threaded into the end of the valve means 45.

A handle 68 is secured to the end of the plug valve 57 in order to rotate the same to open and close the valve means for the flow of air and water to the motor. This handle is received into a recess 69 in the periphery of the valve means 45. The handle 68 is made long enough so that in closed position at least one end of the handle extends beyond the outer periphery of the valve means and so that the end of the handle will engage the tube in which the motor and the valve are inserted. By this construction the motor and valve means cannot be inserted into a tube with the valve means in closed position. In the preferred construction also the two ends of the handle 68 project far enough outwardly in either direction from the valve 57 so that both ends will engage the tube and prevent the motor and valve from being inserted into the tube so long as the valves are in closed position. The handle 68 requires manual movement of the valves to open position to swing the handle into longitudinal alignment or approximate alignment with the motor and valve, in which position the handle is clear of the tube and can be inserted thereto as shown particularly in Figure 6. Since the valve means 45 is directly connected with the motor, the rear end of the valve means carries a soft ring 70 which is preferably of some soft metal which will not score the tube. The front end of the motor or the shell or casing over the motor carries a similar soft ring 71.

It has been mentioned hereinbefore that the air motor drives a cleaning tool. This cleaning tool preferably is a wire brush 75 of any suitable kind. Other forms of cleaning tools may be driven by the tube cleaner described herein, but for the tubes of pasteurizers a brush is more desirable. This brush carries a stud 76 having screw threads 77 which are received into a nipple 78. The nipple is secured to a short length of rubber hose 79, the other end of the hose being secured to a second nipple 80. The nipple 80 carries screw threads 81 which receive the threads 15 on the end of the air motor shaft 10. The cleaning brush 75 therefore is rotated by the air motor.

The wire brush 75 has a diameter less than the inside diameter of the tube and in order that the wire brush may reach the entire inner circumference of a tube being cleaned, it is connected with

the shaft of the air motor through a flexible connection or coupling. This flexible connection, in the broader aspect of the invention, may be any suitable flexible coupling. The rubber hose connection, however, is preferred when the cleaner is used for pasteurizers since a flexible connection of a mechanical type, such as a universal joint, provides rivets and other metallic parts which may break or wear loose and would tend to score the tube. In the construction shown herein, where the rubber hose 79 is used, breakage of the flexible connection will produce no loose metallic parts which would tend to score the tube. It will be observed, therefore, that a construction has been provided giving the maximum degree of safety against scoring of the tube by the cleaner.

Although the valve described herein is particularly suited for use with a tube cleaner, it is to be understood that the valve per se is also a part of the invention, irrespective of in what connection it is used, and irrespective of to what application it may be put. For instance, in the particular application to which this valve is put in this case, it is desirable that both the air and the water be flowing to the air motor before the valve means is inserted into a tube and before the air motor can be inserted very far. It is for this reason that both the air and the water valves are open when the handle is in a position so that the valve means may be inserted into the tube. Applications of the valve means per se are contemplated in which the reverse of this application may be desirable. In other words, in the broader aspect of the invention it is contemplated that the valve means can be inserted into a tube only when the valve means is in one position and is prevented from being inserted into the tube by the handle means when the valve means is in another position.

Various modifications will occur to those skilled in the art in the configuration, composition and disposition of the component elements going to make up the invention as a whole, as well as in the selective combination or application of the respective elements, and no limitation is intended by the phrasology of the foregoing description or illustrations in the accompanying drawings.

What is claimed is:

1. A tube cleaner comprising a compressible fluid driven motor having a cylinder bore, the motor being adapted to be connected with a source of fluid pressure and to drive a tool, one or more liquid outlets in a front face of the fluid motor, and a liquid passage connected with the outlets passing between the cylinder bore and the outer periphery of the motor to the rear of the fluid motor which passage is adapted to be connected with a liquid supply.

2. A tube cleaner comprising a compressible fluid driven motor adapted to be connected with a source of fluid pressure, a shaft projecting from the front of the motor to drive a tool, one or more liquid outlets in the front face of the fluid motor between the outer diameter thereof and the projecting shaft, the outlets being directed so as to project liquid therefrom in the general direction of the tool, the outlets also being directed at an angle so that the liquid is projected at an angle to the face of the motor, and a passage connected with the outlets and passing to the rear of the fluid motor which passage is adapted to be connected with a liquid supply.

3. A tube cleaner comprising a compressible fluid driven motor adapted to be connected with

a source of fluid pressure and to drive a tool, a plurality of liquid outlets at the front of the fluid motor, and a sleeve around the fluid motor and spaced therefrom to form a liquid passage 5 passing to the rear of the fluid motor which passage is adapted to be connected with a liquid supply, the outlets being connected with the liquid passage.

4. A tube cleaner comprising a compressible fluid driven motor adapted to be connected with a source of fluid pressure and to rotate a tool, one or more liquid outlets at the front of the fluid motor and directed outwardly so that the point in the general direction of the cleaning tool 10 and at an angle to the axis of the motor and in the direction of rotation of the cleaning tool, and a sleeve around the fluid motor and spaced therefrom to form a liquid passage passing to the rear of the fluid motor which passage is adapted to be connected with a liquid supply, the liquid outlets being connected with the liquid passage.

5. A tube cleaner comprising a compressible fluid driven motor adapted to be connected with a source of fluid pressure and to rotate a tool, one 15 or more liquid outlets in the front face of the fluid motor and pointed in a general direction towards the tool and at an angle to the axis of the motor so that the liquid is projected in the general direction of rotation of the tool, and a liquid passage connected with the outlet or outlets passing to the rear of the fluid motor which 20 passage is adapted to be connected with a liquid supply.

6. A tube cleaner adapted to be inserted in a tube to be cleaned comprising an air driven motor adapted to be connected with a source of air pressure and to drive a cleaning tool, a water outlet at the front of the air motor, a water passage connected with the water outlet passing 25 to the rear of the air motor which passage is adapted to be connected with a water supply, valve means secured to and following behind the motor into a tube being cleaned and having a plurality of positions to control the air and the water, and a handle means connected with the valve means to move the same from one position to another, the handle means having one position in which the valve means and handle means are insertable within a tube and having at least one 30 outward position in which the valve means and the handle means are prevented from being inserted in a tube because the handle means would engage the end of the tube if it were attempted to be inserted therein, said handle means also preventing movement of the valve means so long as the valve means and handle means are in a tube because outward movement of the valve 35 operating means is prevented by the tube wall.

7. A tube cleaner of the type insertable within a tube comprising a fluid driven motor adapted to be connected with a source of fluid pressure and to drive a cleaning means, valve means secured to and following behind the motor and having a plurality of positions to control the fluid thereto, and a valve operating means connected with the valve means to move the same from one position to another, the valve operating means having one position in which the valve means and the operating means are insertable within a tube and having at least one outward position in which the valve means and the operating means are prevented from being inserted in the tube because the latter means would engage the end of the tube if the cleaner were attempted to be 40 pushed thereinto, said valve operating means also

5 preventing movement of the valve means so long as the valve means and the valve operating means are in a tube because outward movement of the valve operating means is prevented by the tube wall.

8. A tube cleaner of the type which is inserted in a tube comprising a fluid driven motor adapted to be connected with a source of fluid pressure and to drive a cleaning tool, valve means secured to and following behind the motor to control the fluid thereto, and a handle connected with the valve means to open and close the same and being rotatable outwardly when moving the valve means from one of its positions to the other, the handle having a length so that it extends in both directions from its point of attachment with the valve means so that both ends engage the tube and thereby prevent movement of the valve means to another position so long as the valve means is in a tube and prevent insertion of the valve means into the tube when the handle is in its outwardly rotated position, and the handle having a width which enables the valve means to be inserted in the tube when the handle is rotated to an axial position.

9. A tube cleaner for pasteurizers and the like comprising an air driven motor adapted to be connected with a source of air pressure, a cleaning tool having a coupling connecting the cleaning tool with the air motor, a water outlet at the front of the air motor, a water passage connected with the water outlet passing to the rear of the air motor which passage is adapted to be connected with a water supply, valve means secured to and following behind the motor to control the air and the water, and handle means connected with the valve means to open and close the same and being movable outwardly when moving the valve means from open position to closed position so that it engages the tube and thereby prevents movement of the valve means to closed position so long as the handle means is in a tube.

10. A tube cleaner for pasteurizers and the like comprising a fluid driven motor adapted to be connected with a source of fluid pressure, a cleaning tool having a coupling connecting the cleaning tool with the fluid motor, a liquid outlet at the front of the fluid driven motor, valve means secured to and following behind the motor to control the fluid thereto, a liquid passage connecting the outlet with the valve means, and handle means connected with the valve means to open and close the same and being movable outwardly when moving the valve means from open position to closed position so that it engages the tube and thereby prevents the valve means from being in closed position so long as the handle means is in a tube.

11. A tube cleaner comprising a compressible fluid motor adapted to be connected with a source of air pressure and to rotate a cleaning tool including a cylinder and an end cap providing a seal for the end of the cylinder, a fluid port in the end cap leading to the cylinder, and an abutting sleeve engaging the end cap, the abutting sleeve having a central bore connecting with the fluid port in the end cap; a plurality of water outlets at the end of the fluid motor remote from the end cap; a shell around the fluid motor and spaced therefrom to form a water passage passing to the end of the fluid motor adjacent the end cap which passage is adapted to be connected with a water supply, the water outlets being connected with the water passage; a shoulder on the front end of the shell engaging the

cylinder; and a plug threaded upon the rear end of the shell and engaging the abutting sleeve to clamp the shell on the fluid motor and seal the bore in the end cap from the water passage including a fluid passage through the plug connecting with the bore in the abutting sleeve, and a water passage through the plug connecting with the water passage within the shell.

12. A tube cleaner comprising a compressible fluid motor adapted to be connected with a source of fluid pressure and to rotate a cleaning tool including a cylinder and an end cap providing a seal for the end of the cylinder, a fluid port in the end cap leading to the cylinder, and an abutting sleeve engaging the end cap, the abutting sleeve having a central bore connecting with the fluid port in the end cap in all positions; a shell around the fluid motor and spaced therefrom to form a water passage passing to the end of the fluid motor adjacent the end cap which passage is adapted to be connected with a water supply including a flange on the front end of the shell engaging the end of the cylinder remote from the end cap, and a plurality of water outlets through the flange; the water outlets being connected with the water passage; and a plug threaded upon the end of the shell adjacent the end cap and engaging the abutting sleeve to clamp the shell on the fluid motor and seal the bore in the end cap from the

water passage, the plug having fluid passages including a fluid passage in the plug connecting with the bore in the abutting sleeve, and a water passage in the plug connecting with the water passage within the shell.

13. A tube cleaner comprising a compressible fluid motor adapted to be connected with a source of air pressure and to rotate a cleaning tool including a cylinder, a shaft, an end cap providing a bearing for the rear end of the shaft and a seal for the end of the cylinder, a port through the end cap to the cylinder, and a sleeve engaging the end cap to hold it in place, the sleeve having a central bore connecting with the port in the end cap in all positions; a plurality of water outlets at the front of the fluid motor; a shell around the fluid motor and spaced therefrom to form a water passage passing to the rear of the fluid motor which passage is adapted to be connected with a water supply, the water outlets being connected with the water passage; and plug means engaging the end of the sleeve on the motor and screw threaded to the shell to hold the shell upon the motor, the plug means including a fluid passage and a water passage connecting respectively with the central bore in the sleeve and with the water passage within the shell.

JAMES P. RODGERS. 30
